UNITED STATES PATENT OFFICE

BERKELEY S. VAUGHAN, OF GENEVA, ILLINOIS, ASSIGNOR TO WHEELER SCREEN COMPANY, OF GENEVA, ILLINOIS, A CORPORATION OF ILLINOIS

IRONING BOARD

Application filed February 12, 1930. Serial No. 427,714.

My invention relates to an ironing board and particularly to a foldable ironing board. One object is the provision of an ironing board having a folding support which shall be easy to manipulate. Another object is the provision of an ironing board and folding support therefor which shall be of maximum strength or solidity. Another object is the provision of an ironing board support which shall be compact when folded in relation to the ironing board. Another object is the provision of a support for an ironing board which shall resist downward thrust upon the ironing board which in effect holds most efficiently when a downward thrust is applied upon the board. Other objects will appear from time to time in the course of the specification and claims.

I illustrate my invention more or less diagrammatically in the accompanying drawings, wherein—

Figure 1 is side elevation;

Figure 2 is a side elevation with the supports partly folded;

Figure 3 is a section on the line 3—3 of Figure 1;

Figure 4 is an end elevation;

Figure 5 is a rear view of the device with the supports folded;

Figure 6 is a detail;

Figure 7 is a detail;

Figure 8 is a section on the line 8—8 of Figure 7;

Figure 9 is a partial side elevation illustrating a modified form of connection between the support and the board;

Figure 10 is a section on the line 10—10 of Figure 9; and

Figure 11 is a section on the line 11—11 of Figure 10.

Like parts are indicated by like symbols throughout the specification and drawings.

Referring generally to the figures, A indicates an ironing board.

Hinged to one end of the ironing board, for example to the rear end, is the table support, hereafter called the rear support, generally indicated as B and including the side members B¹ which are preferably cross-braced to form a single structural unit. Any

suitable bracing may be employed but I illustrate for example the sheet or strip metal cross-braces B². The member so formed may be pivoted as at B³ B³ to the bottom of the board A and I may employ a transverse base member B⁴ with the lugs B⁵ to receive the pivot bolts B³.

I indicate, as an example of the forward support, a single member C. In the form of Figure 1 this member is pivoted as by the bolt C¹, to the slideable base member C², which member is slideable along the tracks C³ secured to the bottom of the board A. As is shown in Figure 3 the member C² may include the side elements C⁴, horizontal flanges C⁵ which penetrate the space between the tops of the tracks C³ and the bottom of the board A. As the tracks are secured at their ends to the board A they have the function not only of guiding the member C² and thus the end of the member C, but also of providing limiting abutments at each end of the excursion.

Connecting the upper end of the member C and its associated base C² with the rear support B are the braces D D¹. They are carried by the pivot bolt C¹ and extend thence for pivotal connection as at D² D³ with the members B¹ of the rear support B. This connection is shown as roughly midway between top and bottom of the members B¹ but it will be understood that the pivot point, and thus the proportions of the structural members so formed may be varied to suit the particular conditions to be met. I prefer to have the members D D¹ available as both tension and compression members, depending upon where the force is applied to the board A. For this reason I employ rod or rounded stock, to give them the necessary strength or rigidity.

Connecting the lower portion of the support C at the same pivot points D² D³ are the flexible or breakable tension connections each of which includes the member E pivoted as at E¹ to the front support C and the member E² pivoted as at D² or D³. The two members are jointed as at E³, the details of the joint being shown in Figures 6, 7 and 8. E⁴ E⁵ indicate opposed deformations of the

members E, E², adjacent the pivot E³, whereby the joint may be broken in one direction of rotation but is rigid in the other.

Referring to Figures 9, 10 and 11 I may 5 if I wish dispense with the complete extension of the track C³ and substitute therefor a somewhat different connection between the top of the member C and the bottom of the board A. Thus I may secure to the top of 10 the member C a blade G associated with the base G¹, the base G¹ being bolted as by the bolts G², to the top of the member C. The angle between the base G¹ and the blade G represents or conforms to the angular relation 15 between the support C and the board A when it is in final or supporting position. The members D, D¹ in such case may be pivoted directly to the upper portion of the support C, as shown in Figures 9, 10 and 11 and 20 I may employ a bolt D¹⁰. In order to receive 25 the blade G and to hold it against movement in relation to the board, I employ a stirrup G³ which preferably conforms in width rather closely to the width of the blade G, whereby lateral movement of the blade G is prevented.

It will be realized that whereas I have described and shown a practical and operative device, nevertheless many changes might be 30 made in the size, shape, number and disposition of parts without departing from the spirit of my invention. I therefore wish my description and drawings to be taken as in a broad sense illustrative and diagrammatic 35 rather than as limiting me to my specific showing. In particular it will be understood that whereas I have shown my invention as applied to an ironing board I do not wish to be limited to such use, as other applications of or uses for it may be made.

The use and operation of my invention are as follows:

In considering the application of my invention to an ironing board, for which use it 45 is particularly well adapted, it must be understood that an ironing board support should be simple structurally, and should be easy to set up and take down. At the same time it must be strong, and it must be able 50 to support a heavy downward thrust, since the operator, in ironing, applies heavy force to the supporting surface. Also it must resist lateral torsion or thrust, as the weight applied to the top is not limited to a downward 55 dead weight, and the thrust is often at least in part lateral. In connection with providing the necessary support it is important that the substantial extension of one end of the ironing board be left free to provide skirt 60 room, so that articles, such as skirts, may be easily ironed thereon.

It is an advantage of my invention that the supporting structure is of such nature that the more weight is applied the more efficient is the support provided, and the more

intimately or tightly are the various parts of the support held together. That this should be the case should be understood from the nature of the structural elements employed. The rear support B provides a two-point support to the floor. The single front support C, when it is in the supporting position in which it is shown in full line in Figure 1 is rigidly tied to the rear support by four supporting trusses or triangles. Two of these are the triangular supports the first element of each of which is the member C, the second of which is the tension and compression member D D¹ and the third of which is one of the tension connections formed by the members E and E². The third connecting brace or triangle is formed by the member B itself and its connection to the top of the member C, as by the members D D¹. The fourth connection includes the transverse extension of the member B and the tension connections formed by the above described flexible or breakable tension members E E². This system of support converges primarily at the point of connection of the support C and the board A. This point is established by the connection between the blade and the stirrup G³ or by the equivalent connection between the members C⁴ and the right end of the tracks C³, referring to Figure 1. Any downward thrust upon the table consolidates the system of support above described and drives the members C⁴ or the blade G more firmly into final supporting position. The tension members E E² prevent any separation of the lower ends of the front and rear supports. The two triangular structures which extend from the pivots D² D³ hold the upper and lower ends respectively of the member C in rigid relationship with the rear support C. Once the upper end of the front support C is in its full supporting position as in Figure 1, and the two generally vertical triangles, of which it forms part, cannot rotate any farther about the pivots D² D³, then the table A and the upper portion of the rear support B become also incorporated in the supporting structure.

Referring to Figure 1 I then have a quadrangular truss, or rather, two of such trusses, transversely braced, each such truss including as its four elements the member C, the portion of the top A between the upper ends of the two supports, the upper half of the rear support, and finally, the tension connection between the pivots D² or D³ and the pivot E¹. These quadrangular trusses are given rigidity by the transverse tension-compression members D D¹.

This extremely efficient and rigid supporting system is easily made and broken, once the operator ceases to apply pressure to the top of the table. The board A may be tilted into upright position and since no positive locking means are employed, the upper end of the support C is very easily removed from

its point of connection with the board A. In the form of Figure 1 the upper end of the support C is constrained to a single plane of the track C³ and is simply moved forwardly or to the left, referring to Figure 1, until the entire structure is collapsed. The joint between the tension members E and E² is broken upwardly, as shown in dotted line in Figure 1. The lower end of the rear support 5 is swung toward the front of the board and the lower end of the front support is swung towards the rear of the board. This process is shown in intermediate position in Figure 2. When it is completed, as in the 10 position of Figure 5 the front and rear supports lie in the same plane, snugly against the bottom of the board A. The front support is entirely enclosed within the periphery of the board, as is all or substantially all 15 of the bracing or reinforcing structure. The rear support elements B¹ project slightly outwardly from the sides of the board, but none of the supports or supporting structure project longitudinally beyond either end of the 20 board.

In the form of Figures 9, 10 and 11 the supporting structure and supporting principle are the same as above described and the only real difference is that the stirrup G³ in 25 effect an equivalent of the track C³, is effective only when the upper end of the support C is at or near its final supporting position. When the blade G is withdrawn from the stirrup G³ the upper end of the member C 30 is slid outwardly along or moved along the bottom of the board A substantially as if it were constrained by tracks, in the normal operation of the device. While the operator may slide the end of the member C along the bottom of the board it will not much affect the 35 speed or efficiency of the operation if he withdraws it somewhat, in the course of flexing the other members.

An important feature of the device, which 40 will be understood in connection with Figure 1, is the fact that the points of engagement of the front and rear supports substantially underlie the ends of the board. Therefore any downward thrust or weight upon the 45 board will be within the area of support, and will not tend to tilt the board.

In connection with the locking effect and the exertion of pressure, note that there is a double effect by the exertion of such pressure. Referring for example to the form 50 of Figures 9, 10 and 11, the downward thrust of the board, and particularly on the left end of the board positively thrusts the blade G into the stirrup or socket G³. At the same 55 time the tension on the lower members E, E² and the upward thrust on the members D, D¹ to an extent opposes the first mentioned force. There is a neutralization or balance of forces at the point of connection of the front 60 support C with the board.

I claim:

1. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support. 70

2. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support, said compression and tension members being adjacently pivoted to the first support. 75

3. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support, said compression and tension members being concentrically pivoted to the first support. 80

4. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support, said collapsible tension member being hinged intermediate its ends. 100

5. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support, said collapsible tension member being adapted for flexure intermediate its ends. 115

6. In a table, a table top, a support pivotally secured to said top, a second support, a connecting compression member extending from an upper portion of the second support to an intermediate portion of the first support, and a connecting collapsible tension member extending from a lower portion of the second support to the intermediate portion of the first support, the upper end of said second support being slidable in relation to the table top. 120

7. In a table, a table top, a support pivotally secured to said top, a second support, a connecting compression member extending from an upper portion of said second support to said first support, and a connecting collapsible tension member extending from a lower portion of said second support to the first support.

Signed at Geneva, county of Kane and
10 State of Illinois, this 4th day of February,
1930.

BERKELEY S. VAUGHAN.
